Primary Examiner — Leanne Was-Englehart*Assistant Examiner* — Alison Davis(74) *Attorney, Agent, or Firm* — Justin Lampel(57) **CLAIM**

The ornamental design for a hard disk case as shown and described.

DESCRIPTION

FIG. 1 is a front, left and top perspective view of a hard disk case showing my design;

FIG. 2 is a rear, right and bottom perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is an enlarged view of portion 9 shown in FIG. 1; and,

FIG. 10 is an enlarged view of portion 10 shown in FIG. 6.

The broken lines are included for the purposes of illustrating portions of the hard disk case that form no part of the claimed design.

1 Claim, 10 Drawing Sheets(56)
